RAILWAY TRAFFIC CONTROLLING APPARATUS

Joel R. Babcock, Wilmington, N. C., and Ira F. Cadman, St. Louis, Mo., assignors to Westinghouse Air Brake Company, Wilmerding, Pa., a corporation of Pennsylvania

Application October 9, 1951, Serial No. 250,484

13 Claims. (Cl. 246—26)

Our invention relates to railway traffic controlling apparatus. More particularly, our invention relates to apparatus of the type known as traffic locking apparatus, by means of which traffic governing devices such, for example, as signals, for any given stretch of railway track, are, in part, controllable through manually or automatically controlled traffic direction controlling means, and are, in part, controllable by traffic responsive detecting means, for at times directing traffic movements in a given direction over a given stretch of railway track, and for at other times directing traffic movements in the opposite direction over the same stretch of track.

One form of traffic locking apparatus, which has been used, requires joint action by persons at two different control stations for manually controlling traffic movements in both directions over a stretch of railway track. Each of the two control stations may be provided with an interlocking machine, and each interlocking machine may be equipped with a traffic lever which is mechanically interlocked with a signal lever which controls a signal for governing traffic movements onto the corresponding end of the stretch of railway track.

In apparatus embodying our invention, no separate traffic levers are employed. Instead, traffic direction controlling apparatus, in our invention, is controllable by manually operable signal levers and by traffic responsive means. The traffic direction controlling apparatus, in turn, in conjunction with traffic responsive means such, for example, as track relays, controls signals for governing traffic movements in opposite directions over the corresponding stretch of railway track.

In some forms of traffic locking apparatus, traffic direction control circuits are employed which include front contacts of traffic responsive relays, such, for example, as track relays, which are normally energized, but which become deenergized in response to occupation of corresponding portions of a stretch of railway track by a train. In such forms of traffic locking apparatus, the traffic direction control circuits become deenergized when a train enters a corresponding stretch of track, and remain deenergized until the train has left the corresponding stretch of track.

Also, in some forms of traffic locking apparatus, traffic direction control circuits are employed which include a plurality of traffic direction control relays, one for each signal, connected in series.

An object of our invention is the provision of novel and improved traffic locking apparatus, in which only one traffic control relay is employed for each direction of traffic movements over any given stretch of railway track, and in which each of the traffic control relays may be controlled to become energized, while the other traffic control relay remains deenergized, for a train to move in a corresponding direction over the given stretch of railway track, and also in which the traffic control relay which is energized when a train enters the given stretch of track is retained in the energized condition until the given stretch of track again becomes unoccupied.

A feature of our invention, for accomplishing this object, is the provision of a novel and improved traffic locking circuit control arrangement, in which the traffic control relays for both directions of traffic movements are normally deenergized, and in which the signal control circuits for both directions of traffic movements are also normally deenergized.

Another feature of our invention is the provision of an arrangement in which each traffic control relay is located adjacent the leaving end of a stretch of track, for the corresponding direction of traffic movements, and is energized by a circuit which is supplied with current adjacent the opposite or entering end of the stretch of track, and in which each of these circuits is sectioned and is controlled by traffic direction stick relays for retaining the corresponding traffic control relay energized ahead of a train as the train moves over the stretch of track.

Still another feature of our invention is the provision of novel and improved means for controlling an electric lock for a track switch at an intermediate point in a stretch of track.

Another feature of our invention is the provision of novel and improved means for directing traffic movements from an auxiliary track over a track switch at an intermediate point of a stretch of track while the stretch of track is already occupied by a train moving away from the switch.

Applicants' invention, as indicated by the foregoing paragraphs concerning its object and features, relates to a railway traffic locking control arrangement in which only one traffic control relay is employed for each direction of traffic movements over any given stretch of main railway track; in which both traffic control relays are normally deenergized, and the signal control circuits for both directions of traffic movements are also normally deenergized;

in which each of the traffic control relays is located adjacent the leaving end of a stretch of track, for the corresponding direction of traffic movements, and is energized by a circuit which is supplied with current adjacent the opposite or entering end of the stretch of track; in which each of the traffic control circuits includes, and is sectioned by, back contacts of traffic direction stick relays, and is controlled by the traffic direction stick relays for retaining the corresponding traffic control relay energized ahead of a train as the train moves over the stretch of track; in which each of the traffic control relays, upon becoming energized, effects energization of signal control relays for signals for the corresponding direction of traffic movements; in which a switch indication relay for a railway track switch in said stretch of track, upon becoming deenergized, effects energization of each of the traffic control relays; and which includes a traffic stick relay and a first and a second auxiliary direction control relay for controlling the traffic control relays when a train moves over the switch from an auxiliary track to the main track.

We shall describe one form of apparatus embodying our invention, and shall then point out the novel features thereof in claims.

The accompanying drawings, Figs. 1a, 1b, 1c, 1d and 1e, when placed end to end, in the order named, with Fig. 1a on the left, constitute a diagrammatic view showing one form of apparatus embodying our invention for a stretch of main railway track which is provided with a plurality of signals for governing traffic movements in opposite directions over the stretch of main railway track, and which is provided with a track switch at an intermediate point for connecting an auxiliary track with the main track; including a traffic control relay for each direction of traffic movements, each normally deenergized; including control circuits, normally deenergized,

for the plurality of signals for governing traffic movements in opposite directions over the stretch of main track; including means for controlling an electric switch lock for the track switch at an intermediate point in the stretch of main track; and including means for controlling the signals for governing traffic movements in opposite directions away from the track switch at the same time.

Similar reference characters refer to similar parts in the drawings.

Referring further to the drawings, a stretch of main railway track is shown connected, adjacent one of its ends, with an auxiliary track, designated by the reference character X, by a switch 1, and is shown connected, at an intermediate point, with a second auxiliary track, designated by the reference character W, by a switch 5, and is also shown connected, adjacent its other end, with a third auxiliary track, designated by the reference character Z, by a switch 9. In order to simplify the drawings, each track, comprising two parallel series of track rails, is represented by a single line.

The main railway track is divided by insulated joints 10 into sections designated by the reference characters L2T, 1T, R2T, 4T, 5T, 7T, L4T, 9T and R8T. Each of the track sections is provided with a track circuit including a suitable source of current, such, for example, as a battery 11, connected across the rails adjacent one end of the section, and a traffic responsive track relay, designated by the reference character R preceded by the reference character for the corresponding section, connected across the rails adjacent the opposite end of the section.

Signals, designated by the reference characters RA2, RB2, 4S and 6S, govern traffic movements over the stretch of main track toward the right, as shown in the drawings, which we shall assume is the eastbound direction, and a signal, designated by the reference character R8, governs eastbound traffic movements leaving the stretch of track. Signals, designated by the reference characters LA8, LB8, 7S and 3S, govern westbound traffic movements over the stretch of main track, and a signal, designated by the reference character L2, governs westbound traffic movements leaving the stretch of track. The signals may be of any suitable design, such, for example, as the well-known color light type, comprising a green or clear proceed lamp G, a yellow or caution proceed lamp Y, and a red or stop lamp R, as shown in the drawings.

A block for any given signals includes the portion of the track which extends from the given signal to the next signal in advance which governs traffic movements in the same direction as the given signal.

A first traffic control relay, designated by the reference character 2RF, for controlling the signals which direct eastbound traffic movements over the stretch of track, is located adjacent the east end of the stretch of track. A second traffic control relay, designated by the reference character 8LF, for controlling the signals which direct westbound traffic movements, is located adjacent the west end of the stretch of track. Relays 2RF and 8LF are normally connected in a closed circuit path which does not include any source of current, and are therefore normally not energized.

Polarized signal control relays, for controlling the signals which direct traffic movements over the stretch of track, are designated by the reference character HD preceded by the numeral of the reference character for the corresponding signal. These relays are normally not energized. The HD relays which control eastbound signals become energized in response to energization of the first or eastbound traffic control relay 2RF, and the HD relays which control westbound signals become energized in response to energization of the second or westbound traffic control relay 8LF.

The various control circuits can be supplied with energy from any suitable source of current such, for exam-

ple, as a battery Q, having terminals B and N, shown in Fig. 1a.

Energization of the eastbound traffic control relay 2RF can be effected by energization of a first or eastbound traffic locking relay, designated by the reference character 2RTL, shown in Fig. 1a. Energization of the westbound traffic control relay 8LF can be effected by energization of a second or westbound traffic locking relay, designated by the reference character 8LTL, shown in Fig. 1e. Relay 2RTL, when energized, prevents energization of relay 8LF, and relay 8LTL, when energized, prevents energization of relay 2RF. Also, relay 8LF, when energized, prevents energization of relay 2RTL, and relay 2RF, when energized, prevents energization of relay 8LTL.

Energization of the eastbound traffic locking relay 2RTL can be effected, either manually or automatically, through energization of a first polar control relay, designated by the reference character R2HS, of a type, 20 which, when deenergized, retains its contacts in the position to which they were last operated. Relay R2HS has two control windings, designated by the reference characters a and b, respectively. Energization of relay 2RTL will then be continued by circuits including back 25 contacts of relays, designated by the reference characters 2RAS and 1TP, respectively.

Relay 1TP, which we shall refer to as a first track repeater relay, is of the slow pickup type, and is controlled by a front contact of track relay 1TR.

30 Relay 2RAS, which we shall refer to as a first locking stick relay, is associated with signal RA2, and is controlled by relays R2HS and 1TR, and also by a time element device, shown as a relay, designated by the reference character 2TE, and by a route relay, designated by the reference character 2BPR, and by a neutral signal control relay, designated by the reference character RA2H. Time element relay 2TE, is controlled by back contacts of relays 2RAS and RA2H, and by relays R2HS and 2BPR.

Relay 2BPR is controlled by relays R2HS, R2HD 40 and 1TR, and by a normal switch circuit controller contact, designated by the reference character 1WC, operated in conjunction with switch 1, and which is normally closed while switch 1 is in the normal position, but becomes opened when switch 1 is moved to the 45 reverse position.

The control winding a of relay R2HS is controllable manually, by a first signal control lever, designated by the reference character R2V, while a first communication relay, of a slow release type, designated by the 50 reference character 2RP, is energized, and is controllable automatically by a traffic responsive device such, for example, as track relay L2TR, if relay 2RP is deenergized. Control winding b of relay R2HS is controllable by a back contact of relay 1TR.

55 Lever R2V has a normal position n, in which it is shown in Fig. 1a of the drawings, and reverse control positions f and r to the left and right of position n, as shown. Lever R2V is biased toward its n position by suitable means which may, for example, be springs, 60 designated by the reference characters fn and rn connected between lever R2V and fixed blocks, designated by the reference characters fp and rp, respectively.

A second neutral signal control relay, designated by the reference character L2H, is controlled by relay 1TR 65 and by a second signal control lever, designated by the reference character L2V which has a normal position n and a reverse position f.

As shown in Fig. 1a, relay 2RP is normally energized over a communication line, designated by the reference character 12, and is controlled by a manually operable device shown as a push button circuit controller, designated by the reference character 2DB. If the communication line should become broken, or if device 2DB is opened, relay 2RP will become deenergized.

70 Relays 2RP and R2HS may be controlled by appara-

tus which is similar to that which is shown in Letters Patent of the United States No. 2,520,838, granted August 29, 1950, to Thomas W. Hays, for Emergency Control Apparatus for Centralized Traffic Control Systems, except that relay R2HS is shown in the present application as being controlled automatically by an approaching train instead of being controlled manually, as shown in the patent, under an emergency condition in which an emergency relay such as relay 1ER or relay 3ER, shown in the patent, becomes energized. A communication system by which relays 2RP and R2HS may be controlled can be similar to that which is shown in Letters Patent of the United States No. 2,411,375, issued November 19, 1946 to Arthur P. Jackel, for Remote Control Systems. In order to simplify the drawings and specification, however, a simplified diagrammatic control arrangement is shown in the present application.

Signal L2 is controlled by relay L2H so that, while relay L2H is deenergized, lamp R of signal L2 is lighted, and when relay L2H becomes energized, lamp Y or lamp G of signal L2, as selected by traffic conditions in advance of signal L2, not shown, will be lighted.

Signal RA2 is controlled by relays RA2H and R2HD.

A direction stick relay, of a slow release type, designated by the reference character 2RS, will become energized by a pickup circuit when an eastbound train enters section 1T while relay R2HD is energized. Relay 2RS will then remain energized by stick circuits while the train occupies sections 1T and R2T, which constitute the block for signal RA2.

Energization of the second or westbound traffic locking relay 8LTL is controlled, similarly to relay 2RTL, by a second polar control relay, designated by the reference character L8HS, and by back contacts of a second track repeater relay and a second locking stick relay, designated by the reference characters 9TP and 8LAS, respectively, shown in Fig. 1e, all of which are controlled similarly to the corresponding relays shown in Fig. 1a.

A second route relay, designated by the reference character 8BPR, is controlled similarly to relay 2BPR.

A third signal control lever, designated by the reference character L8V, is similar to lever R2V already described.

A second communication relay, designated by the reference character 8LP, shown in Fig. 1e, is controlled similarly to relay 2RP, shown in Fig. 1a.

A third neutral signal control relay, designated by the reference character R8H, shown in Fig. 1e for controlling signal R8, is controlled similarly to relay L2H. A fourth neutral signal control relay, designated by the reference character LA8H, is controlled similarly to relay RA2H.

Signals R8 and LA8 are controlled similarly to the way in which signals L2 and RA2, respectively, are controlled as already described.

A slow release direction stick relay, designated by the reference character 8LS, shown in Fig. 1e, is controlled similarly to relay 2RS, shown in Fig. 1a.

Direction stick relays, designated by the reference characters 3WS and 4ES, associated with signals 3S and 4S, respectively, are controlled similarly to relay 2RS, and each of the relays 3WS and 4ES is also controlled by a back contact of the other, and relay 4ES is also controlled by a front contact of an auxiliary direction control relay, designated by the reference character 4Z.

Direction stick relays, designated by the reference characters 6ES and 7WS, associated with signals 6S and 7S, respectively, are controlled similarly to relays 3WS and 4ES, respectively, the control circuits for relay 7WS including also a front contact of an auxiliary direction control relay 7Z.

Signal control repeater relays are provided for the polarized signal control relays 3HD, 4HD, 6HD and 7HD associated with signals 3S, 4S, 6S and 7S, respectively.

Each of the signal control repeater relays is controlled by a front contact of the corresponding polarized signal control relay, and is of the slow pickup and slow release type. Each of the signal control repeater relays is designated by the reference character P preceded by the reference character for the corresponding polarized signal control relay.

The auxiliary direction control relays 4Z and 7Z are controlled by back contacts of east and west switch lock control relays, designated by the reference characters EAR and WAR, respectively, and by front contacts of a switch indication relay, designated by the reference character NWK, and also by track relays. Relays EAR and WAR will also be referred to as first and second switch lock control relays, respectively.

Track switch 5, located at an intermediate point in the stretch of track shown, is provided with an electric switch lock having a lock magnet, designated by the reference character WL.

A lock bar 14 is rigidly secured to switch 5 for engagement with a dog 15 by means of which the switch may be locked in its normal position, in which it is shown in Fig. 1c of the drawings. Dog 15 is actuated by means of a manually operable switch lock lever which is designated by the reference character 5V, and which has normal and reverse positions designated by the reference characters n and r, respectively.

Movement of lever 5V is controlled by lock magnet WL which has an armature provided with a dog 16 for engagement with notches in a lock segment 17. The armature of magnet WL also operates a back contact 19. Segment 17 is rigidly connected with lever 5V, and is therefore operated by lever 5V.

A switch circuit controller contact 5WC, operated in conjunction with switch 5, is normally closed, but becomes opened when switch 5 is reversed.

Contacts 18 and 139 associated with the switch lock may be operated in any suitable manner such, for example, as by the bow 188 of a padlock P for switch lock lever 5V. When padlock P is removed from the switch lock lever, contact 18 becomes opened and contact 139 becomes closed.

A switch indication relay, designated by the reference character NWK, is controlled by contacts 18 and 19 of padlock P and switch lock control magnet WL, and also by switch contact 5WC, all of which are normally closed, and therefore relay NWK is normally energized while switch 5 is locked in the normal position, shown in Fig. 1c of the drawings.

When contact 18, operated by bow 188 of padlock P, becomes opened, relay NWK becomes deenergized, and its contacts 101, 102, 111 and 112 become opened at their front points, thereby disconnecting relays 4HD and 7HD from their control circuits. Contacts 101, 102, 111 and 112 then become closed at their back points and connect relays EAR and WAR to portions of the control circuits for relays 4HD and 7HD, respectively. At the same time, terminals B and N are connected across conductors 61 and 70, in the closed circuit path for relays 2RF and 8LF, by contacts 173 and 174, respectively, of relay NWK, adjacent switch 5.

A traffic stick relay, designated by the reference character FSR, is controlled to become energized when relay NWK is deenergized while both switch lock control relays EAR and WAR are energized.

Having described, in general, the arrangement and control of the apparatus shown by the accompanying drawings, we shall now describe, in detail, its operation.

As shown by the drawings, all track sections are unoccupied, and therefore all track relays and the track repeater relays 1TP and 9TP are energized; each of the levers R2V, L2V, 5V, R8V and L8V is in the n position; each of the switches 1, 5 and 9 is in its normal position; the reverse polar contact of each of the relays R2HS and L8HS is open; relays 2RP, 2RAS, 4Z, NWK, 7Z, 8LAS,

and 8LP are energized; relays R2HS, 2BPR, L2H, RA2H, R2HD, 8LF, 2RTL, 2RS, 4HDP, 4HD, 3WS, 4ES, 3HD, 3HDP, EAR, FSR, WAR, 6HDP, 6HD, 7WS, 6ES, 7HD, 7HDP, 8LS, 8LTL, 2RF, L8HD, LA3H, R8H, LSHS, and 8BPR are deenergized; time element devices 2TE and 8TE are deenergized; and red lamp R of each of the signals is lighted.

The circuit by which lamp R of signal RA2 is lighted passes from terminal B, through the back point of contact 20 of relay RA2H, and lamp R of signal RA2 to terminal N. Lamp R of signal LA8 is lighted by a circuit which is similar to the circuit just traced for lamp R of signal RA2. Lamp R of signal L2 is lighted by a circuit passing from terminal B, through the back point of contact 22 of relay L2H, and lamp R of signal L2 to terminal N. Lamp R of signal R8 is lighted by a circuit which is similar to the circuit just traced for lamp R of signal L2. Lamp R of signal 3S is lighted by a circuit passing from terminal B, through the back point of contact 23 of relay 3HDP, and lamp R of signal 3S to terminal N. Lamp R of each of the signals 4S, 6S and 7S is lighted by a circuit similar to the circuit just traced for the red lamp R of signal 3S.

Relay 2RP is energized by a circuit passing from terminal B, through circuit controller 2DB, communication line 12, and the winding of relay 2RP to terminal N. Relay 8LP is energized by a circuit which is similar to the circuit just traced for relay 2RP.

Relay 1TP is energized by a circuit passing from terminal B, through contact 34 of relay 1TR, and the winding of relay 1TP to terminal N. Relay 9TP is energized by a circuit which is similar to the circuit just traced for relay 1TP. Relay 2RAS is energized by a stick circuit passing from terminal B, through contact 36 of relay R2HS closed in the normal position, contact 39 of relay RA2H, front point of contact 42 of relay 2RAS, and the winding of relay 2RAS to terminal N. Relay 8LAS is energized by a stick circuit similar to the circuit just traced for relay 2RAS.

Relay 4Z is energized by its circuit which passes from terminal B, through contacts 50 and 51 of relays EAR and NWK, respectively, in multiple, front point of contact 52 of relay 5TR, front point of contact 53 of relay 4TR, and the winding of relay 4Z in multiple with resistor 4t to terminal N. Relay 7Z is energized by a circuit which is similar to the circuit just traced for relay 4Z. Each of the relays 4Z and 7Z is made slow releasing by the resistor connected in multiple with its winding.

Relay NWK is energized by a circuit passing from terminal B, through contact 18 of padlock P, contact 19 of lock magnet WL, switch circuit controller contact 5WC, and the winding of relay NWK to terminal N.

Relays 2RF and 8LF, as shown in the drawings, are connected in series with each other in a closed circuit path without any source of current, this circuit path passing from the winding of relay 8LF, through the back points of contacts 57 and 58 of relays 2RTL and 2RS, respectively, back points of contacts 59 and 60 of relays 3WS and 4ES, respectively, conductor 61, back points of contacts 62 and 63 of relays 7WS and 6ES, respectively, back points of contacts 64 and 65 of relays 8LS and 8LTL, respectively, winding of relay 2RF in multiple with a resistor 2t, back points of contacts 66 and 67 of relays 8LTL and 8LS, respectively, back points of contacts 68 and 69 of relays 6ES and 7WS, respectively, conductor 70, back points of contacts 71 and 72 of relays 4ES and 3WS, respectively, back points of contacts 73 and 74 of relays 2RS and 2RTL, respectively, and the winding of relay 8LF in multiple with resistor 8t. Relays 2RF and 8LF are made slow releasing by the resistors connected in multiple with their windings.

We shall assume that, with the various parts of the apparatus in the condition just described, an eastbound train is to move past signal RA2 over the stretch of track shown in the accompanying drawings between signals

RA2 and LA8. A leverman or a dispatcher will therefore move lever R2V to the r position for effecting energization of winding a of relay R2HS by a reverse control circuit which passes from terminal B, through contact 75 of lever R2V in the r position, front point of contact 77 of relay 2RP, winding a of relay R2HS, front point of contact 78 of relay 2RP, and contact 79 of lever R2V closed in the r position, to terminal N. Relay R2HS will therefore move its contacts 36, 82 and 123 to the reverse or right-hand position as shown in Fig. 1a of the drawings. Lever R2V will then be returned by the springs fn and rn to its normal position n, thereby deenergizing winding a of relay R2HS, but the contacts of relay R2HS will remain in the reverse position to which they have just been operated.

With contact 82 of relay 2RHS closed, relay 2RTL will be energized by a circuit passing from terminal B, through contact 82 of relay R2HS, contact 85 of relay 8LF, and the winding of relay 2RTL to terminal N.

With relay 2RTL energized, relay 2RF will then become energized by a circuit passing from terminal B, through a resistor t, front point of contact 57 of relay 2RTL, and thence over the portion of the closed circuit path, previously traced for relays 2RF and 8LF, which includes the back points of contacts of the direction stick relays and of relay 8LTL, and the winding of relay 2RF, and thence passing through the front point of contact 74 of relay 2RTL to terminal N. Relay 2RF, upon thus becoming energized, will open its back contact 155 in the circuit for relay 8LTL, thereby making it impossible for relay 8LTL to be energized for a westbound traffic movement while relay 2RF is energized for an eastbound traffic movement.

With relay 2RF energized, relay 6HD will become energized by current of reverse polarity passing from terminal B, through a resistor t, contacts 86 and 87 of relays 8LAS and 9TR, respectively, back point of contact 88 of relay R8H, front point of contact 89 of relay 2RF, back point of contact 90 of relay 7HDP, back point of contact 91 of relay 7WS, the winding of relay 6HD, back point of contact 92 of relay 7WS, back point of contact 93 of relay 7HDP, contact 94 of relay L4TR, front point of contact 95 of relay 2RF, and the back point of contact 96 of relay R8H to terminal N. With relay 6HD energized, relay 6HDP will be energized by a circuit passing from terminal B, through contact 97 of relay 6HD, and the winding of relay 6HDP to terminal N.

Relay 6HDP, upon becoming energized, will open its contact 27 at the back point, thereby extinguishing lamp R of signal 6S, and will then complete a circuit for lighting lamp Y of signal 6S, this circuit passing from terminal B, through the front point of contact 27 of relay 6HDP, contact 28 of relay 6HD closed in the reverse position, and lamp Y of signal 6S to terminal N.

With relay 6HDP energized, relay 4HD will be energized by current of normal polarity passing from terminal B, through a resistor t, front point of contact 98 of relay 6HDP, contact 99 of relay 7TR, back point of contact 100 of relay FSR, front points of contacts 101 and 102 of relay NWK, back point of contact 103 of relay FSR, contact 104 of relay 5TR, contact 105 of relay 4TR, back point of contact 106 of relay 3HDP, back point of contact 107 of relay 3WS, winding of relay 4HD, back point of contact 108 of relay 3WS, back point of contact 109 of relay 3HDP, back point of contact 110 of relay FSR, front points of contacts 111 and 112 of relay NWK, back point of contact 113 of relay FSR, and the front point of contact 114 of relay 6HDP to terminal N. With relay 4HD energized, relay 4HDP will be energized by a circuit similar to the circuit previously traced for relay 6HDP.

With relay 4HD energized by current of normal polarity, and with relay 4HDP energized, lamp R of signal 4S will be extinguished, and a circuit will be completed for lighting lamp G of signal 4S, this circuit passing from

terminal B, through the front point of contact **25** of relay **4HDP**, contact **26** of relay **4HD** closed in the normal position, and lamp **G** of signal **4S** to terminal **N**.

With relay **4HDP** energized, relay **R2HD** will be energized by current of normal polarity passing from terminal **B**, through a resistor **t**, front point of contact **116** of relay **4HDP**, contact **117** of relay **R2TR**, back point of contact **118** of relay **8LF**, winding of relay **R2HD**, back point of contact **119** of relay **8LF**, and the front point of contact **120** of relay **4HDP** to terminal **N**.

With relay **R2HD** energized, a circuit will be completed for energizing relay **2BPR**, this circuit passing from terminal **B**, through contact **121** of relay **R2HD**, contact **122** of relay **1TR**, switch circuit controller contact **1WC**, contact **123** of relay **R2HS**, and the winding of relay **2BPR** to terminal **N**. With contact **36** of relay **R2HS** closed in the reverse position, and with contact **37** of relay **2BPR** closed at its front point, relay **2RAS** will become deenergized.

With relay **2RAS** deenergized, a circuit will be completed for retaining relay **2RTL** energized, this circuit being the same as the circuit previously traced for relay **2RTL** except that it includes contact **84** of relay **2RAS** instead of contact **82** of relay **R2HS**. With relay **2RAS** deenergized, a circuit will now be completed for energizing relay **RA2H**, this circuit passing from terminal **B**, through contact **36** of relay **R2HS** closed in the reverse position, front point of contact **37** of relay **2BPR**, contact **38** of relay **2RAS**, and the winding of relay **RA2H** to terminal **N**.

With relay **RA2H** energized, and relay **R2HD** energized by current of normal polarity, lamp **R** of signal **RA2** will be extinguished, and lamp **G** of this signal will be lighted by a circuit passing from terminal **B**, through the front point of contact **20** of relay **RA2H**, contact **21** of relay **R2HD** closed in the normal position, and lamp **G** of signal **RA2** to terminal **N**.

We shall assume further that a leverman or dispatcher will now move lever **R8V** to its **r** position, thereby completing a circuit for energizing relay **R8H**, this circuit passing from terminal **B**, through contact **124** of lever **R8V**, contact **125** of relay **9TR**, and the winding of relay **R8H** to terminal **N**. Lamp **R** of signal **R8** will therefore be extinguished, and lamp **Y** or lamp **G** of signal **R8** will be lighted according to traffic conditions in advance, over a circuit which passes from terminal **B**, through the front point of contact **33** of relay **R8H**, and selecting means not shown in the drawings.

With relay **R8H** energized, relay **6HD** will be energized by current of normal polarity in a circuit which is the same as the circuit previously traced for this relay except that it includes the front points of contacts **88** and **96** of relay **R8H** instead of the back points of these contacts. With relay **6HD** energized by current of normal polarity, lamp **Y** of signal **6S** will be extinguished, and lamp **G** of this signal will become lighted by a circuit which is the same as the circuit previously traced for lamp **Y** except that it includes contact **28** of relay **6HD** in the normal position.

When an eastbound train now passes signal **RA2** onto section **1T**, relay **1TR** will become deenergized, causing its contact **122** to open, and thereby also deenergize relay **2BPR**. Relay **2BPR**, upon becoming deenergized, will open, at the front point of its contact **37**, the circuit previously traced for relay **RA2H**, causing relay **RA2H** to become deenergized. With relay **RA2H** deenergized, lamp **G** of signal **RA2** will be extinguished, and lamp **R** of this signal will again be lighted by its circuit previously traced. Relay **1TR**, upon becoming deenergized, completes a circuit for energizing winding **b** of relay **R2HS**, this circuit passing from terminal **B**, through contact **81** of relay **1TR**, and winding **b** of relay **R2HS** to terminal **N**. With winding **b** of relay **R2HS** thus energized, contacts **36**, **82** and **123** of relay **R2HS** will be returned to their normal positions shown in the drawings.

With contact **36** of relay **R2HS** closed in the normal position, and with contact **39** of relay **RA2H** now closed because of relay **RA2H** being deenergized, relay **2RAS** will become energized by a pickup circuit passing from terminal **B**, through contact **36** of relay **R2HS** closed in the normal position, contact **39** of relay **RA2H**, contact **40** of relay **1TR**, and the winding of relay **2RAS** to terminal **N**. Relay **2RAS**, upon becoming energized, will complete its own stick circuit previously traced.

With relay **1TR** deenergized, relay **1TP** will in turn also be deenergized because of the opening of contact **34** of relay **1TR**. Relay **2RTL** will now be retained in the energized condition by a third circuit which is the same as the circuit first traced for this relay except that it includes the back point of contact **83** of relay **1TP** instead of contact **82** of relay **R2HS**.

With relay **1TP** deenergized while relay **R2HD** is energized, a pickup circuit will also be completed for relay **2RS**, this circuit passing from terminal **B**, through contact **126** of relay **1TP**, front point of contact **127** of relay **R2HD**, and the winding of relay **2RS** to terminal **N**. Relay **2RS**, upon becoming energized, will complete a stick circuit for itself, which is the same as the pickup circuit just traced except that it includes contact **128** of relay **2RS** instead of the front point of contact **127** of relay **R2HD**.

With relay **2RS** energized, the circuit previously described for relay **2RF** including the back points of contacts **58** and **73** of relay **2RS** will be interrupted, but the energization of relay **2RF** will be continued by a circuit including the front points of contacts **58** and **73** of relay **2RS** and the back points of the contacts of the rest of the direction stick relays and of relay **8LTL**. It will be noted that the new circuit for relay **2RF** does not include any contact of relay **2RTL** as in the case of the first circuit described for relay **2RF**.

When the eastbound train enters section **R2T**, deenergizing relay **R2TR**, relay **R2HD** will be deenergized because of the opening of contact **117** of relay **R2TR**. With relay **R2HD** deenergized, a second stick circuit will be completed for relay **2RS**, this circuit passing from terminal **B**, through the back point of contact **27** of relay **R2HD**, contact **128** of relay **2RS**, and the winding of relay **2RS** to terminal **N**. Relay **2RS** will therefore remain energized, by this circuit, as long as relay **R2HD** is deenergized.

When the train leaves section **1T**, relay **1TR** and, in turn, relay **1TP** will become energized, thereby opening the first stick circuit traced for relay **2RS** which will, however, remain energized by the second stick circuit, traced through the back point of contact **127** of relay **R2HD**. Relay **2RTL** will now be deenergized by the opening of contact **83** of relay **1TP**.

When the train enters section **4T**, deenergizing relay **4TR**, relay **4HD** will be deenergized by the opening of contact **105** of relay **4TR**. Relay **4HDP** will therefore in turn also be deenergized by the opening of contact **115** of relay **4HD**. With relay **4HDP** deenergized, lamp **G** of signal **4S** will be extinguished, and lamp **R** will again be lighted by its circuit previously described. With relay **4TR** deenergized, the circuit previously traced for relay **4Z** will be opened at the front point of contact **53** of relay **4TR**, but a second circuit will now be completed for energizing relay **4Z**, this circuit passing from terminal **B**, through the back point of contact **53** of relay **4TR**, and the winding of relay **4Z** in multiple with resistor **4t** to terminal **N**. Relay **4HDP**, on account of being of the slow pickup, slow release type, does not at once open its front contacts when it becomes deenergized.

A pickup circuit is therefore completed, for a brief period of time, for relay **4ES**, this circuit passing from terminal **B**, through contact **129** of relay **4TR**, front point of contact **130** of relay **4HDP**, contacts **132** and **133** of relays **3WS** and **4Z**, respectively, and the winding of relay **4ES** to terminal **N**. Relay **4ES**, upon becoming ener-

gized, completes a stick circuit which is the same as the pickup circuit just traced except that it includes contact 131 of relay 4ES instead of the front point of contact 130 of relay 4HDP. When relay 4HDP releases its contacts, a second stick circuit will be completed for relay 4ES which is the same as the first stick circuit described for this relay except that it includes the back point of contact 130 of relay 4HDP instead of contact 129 of relay 4TR.

With relay 4ES energized, relay 2RF will be retained energized over a circuit including the front points of contacts 60 and 71 of relay 4ES and a portion of the closed circuit path traced for relays 2RF and 8LF which is shorter than the portions included in the previous circuits traced for relay 2RF, and which does not include contacts of relays 2RS and 3WS.

When the train leaves section R2T, relay R2HD will become energized by current of reverse polarity in a circuit which is the same as the circuit previously traced for this relay except that it includes the front points of contacts 134 and 135 of relay 4ES and the back points of contacts 120 and 116 of relay 4HDP, instead of the front points of contacts 116 and 120 of relay 4HDP. With relay R2HD energized, the second stick circuit traced for relay 2RS through the back point of contact 127 of relay R2HD will be opened, and therefore relay 2RS will become deenergized.

If the leverman or dispatcher now again moves lever R2V to the *r* position for energizing winding *a* of relay R2HS by current of reverse polarity, as previously described, relay 2BPR will again be energized, causing relay 2RAS to be deenergized and relay RA2H in turn to again become energized, as previously described. With relay RA2H energized, and with relay R2HD energized by current of reverse polarity, lamp R of signal RA2 will be extinguished, and lamp Y of this signal will be lighted by a circuit passing from terminal B, through the front point of contact 20 of relay RA2H, contact 21 of relay R2HD closed in the reverse position, and lamp Y of signal RA2 to terminal N.

When the train enters section 5T, the circuit for relay 4HD will be opened at a second point because of the opening of contact 104 of relay 5TR.

When the train enters section 7T, the circuit for relay 4HD will be opened at another point by the opening of contact 99 of relay 7TR. Relay 7Z will now be energized by a second circuit, passing from terminal B, through the back point of contact 56 of relay 7TR, and the winding of relay 7Z in multiple with resistor 7t to terminal N.

When the train leaves section 4T, relay 4Z will be energized by a third circuit, passing from terminal B, through the back point of contact 52 of relay 5TR, front point of contact 53 of relay 4TR, and the winding of relay 4Z in multiple with resistor 4t to terminal N. Also, when the train leaves section 4T, the stick circuit first described for relay 4ES will be opened at contact 129 of relay 4TR, but relay 4ES will be retained in the energized condition by the second stick circuit, described for this relay, through the back point of contact 130 of relay 4HDP.

When the train leaves section 5T, relay 4Z will again become energized by its circuit first traced.

When the train enters section L4T, relay 6HD will become deenergized because of the opening of contact 94 of relay L4TR in the energizing circuit for relay 6HD. With relay 6HD deenergized, relay 6HDP will also become deenergized, but before relay 6HDP releases its contacts, relay 6ES will become energized by a pickup circuit which is similar to the pickup circuit previously traced for relay 4ES. Relay 6ES, upon becoming energized, will complete a stick circuit which is similar to the stick circuit also previously described for relay 4ES. When relay 6HDP releases its contacts, a second stick circuit will be completed for relay 6ES which is similar to the second stick circuit previously described for relay 4ES.

With relay 6ES energized, relay 2RF will be retained energized by a circuit including the front points of contacts 63 and 68 of relay 6ES and which includes a still shorter portion of the closed circuit path previously traced for relays 2RF and 8LF, including contacts of only relays 8LS and 8LTL in addition to the contacts of relay 6ES.

When the train leaves section 7T, relay 7Z will again be energized by its circuit first traced. Relay 4HD will now be energized by current of reverse polarity in a circuit which is the same as the circuit previously traced for this relay except that it includes the front points of contacts 144 and 145 of relay 6ES and the back points of contacts 114 and 98 of relay 6HDP instead of the front points of contacts 98 and 114 of relay 6HDP. With relay 4HD again energized, relay 4HDP will also become energized, thereby opening the second stick circuit described for relay 4ES, and causing relay 4ES to be deenergized. With relay 4HDP again energized, relay R2HD will again be energized by current of normal polarity in the circuit previously traced for this relay.

When the train enters section 9T, deenergizing relay 9TR, relay R8H will become deenergized by the opening of contact 125 of relay 9TR in the circuit previously traced for relay R8H. With relay R8H deenergized, lamp R of signal R8 will again be lighted by its circuit previously traced. The circuit for relay 6HD will now be opened at another point by the opening of contact 87 of relay 9TR.

When the train leaves section L4T, relay 6HD will still be deenergized because contact 87 of relay 9TR will still be open. The first stick circuit described for relay 6ES, including contact 140 of relay L4TR will now be opened, but the second stick circuit for relay 6ES, including the back point of contact 141 of relay 6HDP will still be closed, and therefore relay 6ES will still be energized.

When the train leaves section 9T, relay 6HD will again become energized by current of normal polarity if lever R8V is in the *r* position so that relay R8H again becomes energized, or relay 6HD will become energized by current of reverse polarity if relay R8H is deenergized because of lever R8V having been returned to the *n* position, or if relay R8H were controlled by a front contact of relay R8TR. With relay 6HD energized, relay 6HDP will in turn become energized, thereby opening the second stick circuit for relay 6ES and causing relay 6ES to become deenergized.

If the dispatcher has not again energized relay R2HS for a following train, and if there is no following train on the stretch of track, causing one of the direction stick relays to be energized, relay 2RF will now become deenergized, and in turn relays 6HD, 4HD and R2HD will also become deenergized.

If, however, the dispatcher has effected the energization of winding *a* of relay R2HS by moving lever R2V to the *r* position, thereby causing relay 2RTL to be energized, or if a following train has entered the stretch of track, causing one of the direction stick relays to become energized, relay 2RF will remain energized as long as the following train occupies the stretch of track, or as long as relay 2RTL remains energized because of contact 82 of relay R2HS being closed in the reverse position.

We shall next assume that all parts of the apparatus are again in the normal condition, and that a leverman or a dispatcher again effects energization of relay R2HD for controlling signal RA2 to display a proceed indication, as previously described. We shall assume further that the leverman or dispatcher then decides to cause signal RA2 to again display the stop indication before the east-bound train passes this signal.

The leverman or dispatcher will therefore move lever R2V to the *f* position, so that winding *a* of relay R2HS will become energized by current of normal polarity, passing from terminal B, through contact 79 of lever R2V, front point of contact 78 of relay 2RP, winding *a* of relay

R2HS, front point of contact 77 of relay 2RP, and contact 75 of lever R2V closed in the *f* position, to terminal N. With winding *a* of relay R2HS energized by current of normal polarity, contact 36 of relay R2HS will be moved to the normal position, thereby deenergizing relay RA2H.

With relay RA2H deenergized, a circuit will be completed for energizing time element device 2TE, passing from terminal B, through contact 36 of relay R2HS closed in the normal position, contact 39 of relay RA2H, back point of contact 42 of relay 2RAS, and the winding of time element relay 2TE to terminal N. Upon the lapse of a measured period of time, relay 2TE will close its contact 41, thereby completing a circuit for energizing relay 2RAS, this circuit passing from terminal B, through contact 36 of relay R2HS closed in the normal position, contact 39 of relay RA2H, contact 41 of time element relay 2TE, and the winding of relay 2RAS to terminal N.

Contact 84 of relay 2RAS, and also contact 82 of relay R2HS will now be open, thereby causing relay 2RTL to become deenergized. With relay 2RTL deenergized, relay 2RF will in turn be deenergized, causing relays 6HD, 4HD and R2HD to be deenergized successively.

We shall now assume that all parts are again in the normal condition, and that the communication line 12 fails, so that relay 2RP is deenergized. If, now, an eastbound train enters section L2T, winding *a* of relay R2HS will become energized by current of reverse polarity passing from terminal B, through the back point of contact 76 of relay L2TR, back point of contact 77 of relay 2RP, winding *a* of relay R2HS, back point of contact 78 of relay 2RP, and the back point of contact 80 of relay L2TR to terminal N. With winding *a* of relay R2HS energized by current of reverse polarity, contact 82 of relay R2HS will close the circuit previously traced for relay 2RTL, causing relay 2RTL to again become energized as previously described. With relay 2RTL energized, relay 2RF, and in turn, relays 6HD, 4HD and R2HD will be energized as also previously described, so that the corresponding signals will again display proceed indications for the eastbound train.

When the train enters section 1T signal RA2 will be controlled to display the stop indication, and relay 2RAS will again become energized by its first pickup circuit, previously traced.

When the train leaves section L2T, winding *a* of relay R2HS will become energized by current of normal polarity, passing from terminal B, through the front point of contact 80 of relay L2TR, back point of contact 78 of relay 2RP, winding *a* of relay R2HS, back point of contact 77 of relay 2RP, and the front point of contact 76 of relay L2TR to terminal N. The operation of the apparatus as the train proceeds further will then be similar to that previously described for an eastbound train movement over the stretch of track.

We shall now assume that the energization of winding *a* of relay R2HS by current of reverse polarity is again effected, either manually or automatically, for clearing the eastbound signals. We shall assume further that an eastbound train then proceeds over the stretch of track as far as section 5T, and stops on section 5T, preparatory to moving over switch 5 in the reverse position to track W.

A trainman will then unlock switch 5 by removing padlock P, thereby opening contact 18 and closing contact 139 of padlock P. With contact 18 of padlock P opened, relay NWK will be deenergized. With relay NWK deenergized, terminals B and N will be connected with conductors 61 and 70, respectively, adjacent switch 5, through a resistor *t* and contacts 173 and 174, respectively, of relay NWK.

Relay 2RF will then be retained in the energized condition by a circuit including contacts 173 and 174 of relay NWK and the portion of the closed circuit path previously traced for relays 2RF and 8LF between switch 5 and relay 2RF.

With relay 5TR deenergized, and with contact 139 of padlock P closed, a circuit will be completed for energizing the winding of lock magnet WL, this circuit passing from terminal B, through contact 136 of relay 5TR, contact 139 of padlock P, and the winding of magnet WL to terminal N. With the winding of magnet WL energized, dog 16 will be lifted out of engagement with segment 17, thereby permitting lever 5V to be moved to the *r* position for withdrawing dog 15 from engagement with lock bar 14. A trainman will then move switch 5 to the reverse position.

With relay NWK deenergized, relay 4HD will be disconnected, at the front points of contacts 102 and 111 of relay NWK, from the portion of its control circuit east of switch 5. Relay EAR will then be connected with the east portion of the control circuit for relay 4HD through the back points of contacts 101 and 112 of relay NWK, and relay WAR will be connected with the west portion of the control circuit for relay 4HD through the back points of contacts 102 and 111 of relay NWK.

When the train has moved over switch 5 onto track W, and a trainman restores switch 5 to its normal position and returns lever 5V to its *n* position, and also restores the padlock P to the position in which it locks lever 5V, relay NWK will again become energized by its circuit previously traced.

With relay NWK again energized, its contacts 173 and 174 will be opened, and relay 2RF will again be energized by its circuit which includes the front points of contacts 60 and 71 of relay 4ES. With track sections 4T, 5T, and 7T again unoccupied, relay 4HD will again become energized, causing relay 4HDP to also, in turn become energized. Relay 4HDP, upon becoming energized, will open the second stick circuit for relay 4ES, causing relay 4ES to become deenergized, which will then deenergize relay 2RF. With relay 2RF deenergized, the eastbound signals will again be controlled to display the stop indication.

When the train is ready to leave track W and return to the main track over switch 5, a trainman will again

remove padlock P, causing relay NWK to again be deenergized. With relay NWK deenergized, relay 2RF will again be energized by its circuit which includes contacts 173 and 174 of relay NWK, and relay 8LF will also be energized by a similar circuit which includes these contacts. Relay 6HD will then again become energized as previously described, and relay 3HD will also, similarly, become energized. With relay 3HD energized, relay 3HDP will become energized by its circuit passing from terminal B, through contact 177 of relay 3HD, and the winding of relay 3HDP to terminal N.

With relay 3HDP energized and relay NWK deenergized, relay WAR will be energized by a circuit passing from terminal B, through a resistor *t*, front point of contact 106 of relay 3HDP, contact 105 of relay 4TR, contact 104 of relay 5TR, back point of contact 103 of relay FSR, back point of contact 102 of relay NWK, winding of relay WAR, back points of contacts 111 and 110 of relays NWK and FSR, respectively, and the front point of contact 109 of relay 3HDP to terminal N. With relay 6HDP energized on account of relay 6HD being energized and with relay NWK deenergized, relay EAR will be energized by a circuit passing from terminal B, through a resistor *t*, front point of contact 98 of relay 6HDP, contact 99 of relay 7TR, back points of contacts 100 and 101 of relays FSR and NWK, respectively, winding of relay EAR, back points of contacts 112 and 113 of relays NWK and FSR, respectively, and the front point of contact 114 of relay 6HDP to terminal N.

With relays EAR and WAR energized, a second circuit will be completed for energizing the winding of lock magnet WL, this circuit passing from terminal B, through contacts 137 and 138 of relays EAR and WAR, respectively, contact 139 of padlock P, and the winding of magnet WL to terminal N. A trainman will then move lever 5V to its *r* position, thereby withdrawing dog 15 from

lock bar 14, and will then move switch 5 to the reverse position.

With relay NWK deenergized, and with relays EAR and WAR energized, a pickup circuit will be completed for energizing relay FSR, this circuit passing from terminal B, through contact 169 of relay NWK, front points of contacts 170 and 171 of relays WAR and EAR, respectively, and the winding of relay FSR in multiple with a resistor Ft, to terminal N. With resistor Ft connected in multiple with the winding of relay FSR, relay FSR will be slow releasing. Relay FSR, upon becoming energized by the pickup circuit just traced, will complete a stick circuit passing from terminal B, through contact 169 of relay NWK, contact 172 of relay FSR, and the winding of relay FSR in multiple with resistor Ft, to terminal N.

When the train on track W enters section 7T, contact 99 of relay 7TR will open the circuit traced for relay EAR, causing relay EAR to be deenergized. With relay EAR deenergized, a second stick circuit will be completed for relay FSR, this stick circuit passing from terminal B, through the back point of contact 171 of relay EAR, front point of contact 170 of relay WAR, contact 172 of relay FSR, and the winding of relay FSR in multiple with a resistor Ft to terminal N.

When the train enters section 5T, contact 104 of relay 5TR will open the circuit traced for relay WAR, causing relay WAR to also be deenergized. Relay FSR will now remain energized by its stick circuit first traced. With relay WAR deenergized, a third stick circuit will also be completed for relay FSR, passing from terminal B, through the back point of contact 170 of relay WAR, contact 172 of relay FSR, and the winding of relay FSR in multiple with resistor Ft to terminal N.

After the train has moved over switch 5 onto the main track, a trainman will return switch 5 to the normal position, and will restore padlock P to the position for locking lever 5V. Relay NWK will then again become energized by its circuit previously traced.

With relay NWK energized, its contacts 173 and 174 will be opened, but relays 2RF and 8LF will be retained in the energized condition by current supplied to conductors 61 and 70 adjacent switch 5, through a resistor t, over front contacts 175 and 176 of relay FSR. With relay FSR energized, if the train has moved off of section 7T, relay EAR will now be energized over a circuit similar to the circuit previously traced for this relay except that it includes the front points of contacts 100 and 113 of relay FSR instead of the back points of these contacts and the back points of contacts 101 and 112 of relay NWK.

If, now, the train moves westward and enters section R2T at signal 3S, relay 3WS will become energized by a pickup circuit passing from terminal B, through contact 178 of relay R2TR, front point of contact 179 of relay 3HDP, contact 181 of relay 4ES, and the winding of relay 3WS to terminal N. Relay 3WS, upon becoming energized, will complete a stick circuit passing from terminal B, through contact 178 of relay R2TR, contact 180 of relay 3WS, contact 181 of relay 4ES, and the winding of relay 3WS to terminal N.

With relay 3WS energized, relay 8LF will now be energized by a circuit passing from terminal B, through a resistor t, front point of contact 59 of relay 3WS, the portion of the closed circuit path for relays 2RF and 8LF between signal 3S and relay 8LF, and the front point of contact 72 of relay 3WS to terminal N.

When the train leaves section 4T, relay WAR will become energized by a circuit passing from terminal B, through a resistor t, front point of contact 108 of relay 3WS, back point of contact 109 of relay 3HDP, front point of contact 110 of relay FSR, winding of relay WAR, front point of contact 103 of relay FSR, contacts 104 and 105 of relays 5TR and 4TR, respectively, back point of contact 106 of relay 3HDP, and the front point of contact 107 of relay 3WS to terminal N. Relay WAR, upon

becoming energized, will open the third stick circuit traced for relay FSR, causing relay FSR to become deenergized.

With relay FSR deenergized, relay 2RF, and also relay 5 EAR, will become deenergized. With relay 3WS energized, relay FSR deenergized, and relay NWK energized, relay 7HD will now become energized by current of reverse polarity, by a circuit similar to the circuit previously traced for relay 4HD for eastbound traffic movements. With relay 7HD energized, relay 7HDP will be energized by its circuit including contact 163 of relay 7HD. With relay 7HDP energized, relay L8HD will now be energized by current of normal polarity in a circuit which is similar to the circuit previously traced for energizing relay R2HD by current of normal polarity for eastbound traffic movements. A leverman or dispatcher could, if he so desired, now effect energization of relay L8HS, and thereby cause relay 8BPR to become energized, and in turn cause relay LA8H to become energized to control signal LA8 to display a proceed indication for a following westbound train.

We shall assume that, instead of proceeding westward, the train leaving track W reverses its direction and moves eastward over switch 5 in the normal position toward signal 6S. While the train is on section 5T or section 4T, relay WAR will be deenergized, so that relay FSR will be energized by its third stick circuit previously described.

When the train enters section 7T, relay EAR will become deenergized. Then, when the train has left sections 4T and 5T, relay WAR will again become energized, but relay FSR, being slow releasing, will now remain energized by its second stick circuit, previously traced through the back point of contact 171 of relay EAR and the front point of contact 170 of relay WAR.

When the train enters section L4T at signal 6S, relay 6ES will become energized by a pickup circuit which is similar to the pickup circuit previously traced for relay 3WS. With relay 6ES energized, relay 2RF will be energized by a circuit passing from terminal B, through a resistor t, front point of contact 63 of relay 6ES, and the portion of the closed circuit path for relays 2RF and 8LF between signal 6S and relay 2RF, and the front point of contact 68 of relay 6ES to terminal N.

When the train leaves section 7T, relay EAR will become energized by a circuit passing from terminal B through a resistor t, front point of contact 144 of relay 6ES, back point of contact 114 of relay 6HDP, front point of contact 113 of relay FSR, winding of relay EAR, front point of contact 100 of relay FSR, contact 99 of relay 7TR, back point of contact 98 of relay 6HDP, and the front point of contact 145 of relay 6ES to terminal N. With relay EAR energized, the second stick circuit previously traced for relay FSR will be opened at the back point of contact 171 of relay EAR, so that relay FSR will become deenergized, causing relay 8LF to in turn also be deenergized.

We shall now assume that, while an eastbound train occupies section 7T, a trainman removes padlock P for a second train to move from track W over switch 5 to the main track. Relay NWK will be deenergized, as previously described, when the trainman removes padlock P from lever 5V.

Relay EAR will become energized, as previously described, when the eastbound train leaves section 7T. With relay NWK deenergized and with relay EAR energized, relay 4Z will become deenergized, causing relay 4ES to in turn also become deenergized.

Relay 8LF will then become energized on account of relay NWK being deenergized, as previously described. With relay 8LF energized, relay 3HD will again become energized, causing relay WAR to in turn also become energized. With relays EAR and WAR energized, the winding of switch lock magnet WL will again be energized, as previously described, so that the leverman can move lever 5V to its r position and then move switch 5

to its reverse position for the second train to leave track W. We have described, for a few typical traffic movements, the operation of one form of apparatus embodying our invention. It is believed that, in view of such description, the operation of the apparatus for any other possible traffic movement can be readily traced by referring to the accompanying drawings.

Although we have herein shown and described only one form of apparatus embodying our invention, it is understood that various changes and modifications may be made therein within the scope of the appended claims without departing from the spirit and scope of our invention.

Having thus described our invention, what we claim is:

1. In railway traffic controlling apparatus for a stretch of railway track which is provided with a plurality of signals for governing traffic movements in a given or first direction and in the opposite or second direction over said stretch of track which comprises a plurality of blocks one for each signal for each direction of traffic movements, the combination comprising, a first traffic control relay, a second traffic control relay, a first traffic locking relay, a second traffic locking relay, a plurality of direction stick relays one for each of said signals, means controlled by a train upon passing each of said signals while the signal is controlled to display a proceed indication for energizing the corresponding direction stick relay and for then keeping the direction stick relay energized while the corresponding signal is controlled to display a stop indication, first manually controllable means for energizing said first traffic locking relay, means controlled by a front contact of said first traffic locking relay for energizing said first traffic control relay by a first main traffic control circuit including back contacts of said direction stick relays and of said second traffic locking relay, means controlled by said first traffic control relay while energized for controlling the signals for said first direction to display proceed indications, means controlled by said direction stick relays for signals for traffic movements in said first direction upon becoming energized consecutively in response to a train moving over said stretch of track for retaining said first traffic control relay energized over consecutively smaller portions of said first main traffic control circuit, second manually controllable means for energizing said second traffic locking relay, means controlled by a front contact of said second traffic locking relay for energizing said second traffic control relay by a second main traffic control circuit including said back contacts of said direction stick relays and a back contact of said first traffic locking relay, means controlled by said second traffic control relay while energized for controlling the signals for said second direction to display proceed indications, means controlled by said direction stick relays for signals for traffic movements in said second direction upon becoming energized consecutively in response to a train moving over said stretch of track for retaining said second traffic control relay energized over consecutively smaller portions of said second main traffic control circuit, and traffic responsive means for controlling each of said signals to display a stop indication if the first block in advance of the corresponding signal is occupied by a train.

2. In railway traffic controlling apparatus for a stretch of railway track which is provided with a plurality of signals for governing traffic movements in a given or first direction and in the opposite or second direction over said stretch of track, the combination comprising, a first traffic control relay, a second traffic control relay, a first traffic locking relay, a second traffic locking relay, a plurality of direction stick relays one for each of said signals, means controlled by a train upon passing each of said signals while the signal is controlled to display a proceed indication for energizing the corresponding direction stick relay and for then keeping the direction stick relay energized while the stretch of track is occupied between the corresponding signal and the next signal in advance which

5 10 15 20 25 30 35 40 45 50 55 60 65 70

governs traffic movements in the same direction, first manually controllable means for energizing said first traffic locking relay, means including a front contact of said first traffic locking relay for energizing said first traffic control relay over a first main traffic control circuit which includes a back contact of each of said direction stick relays and of said second traffic locking relay, means controlled by said first traffic control relay while energized for controlling the signals for said first direction to display proceed indications, means controlled by said direction stick relays for signals for traffic movements in said first direction upon becoming energized in response to a train moving over said stretch of track for retaining said first traffic control relay energized over consecutively shorter portions of said first main traffic control circuit, a second manually controllable means for energizing said second traffic locking relay, means including a front contact of said second traffic locking relay for energizing said second traffic control relay by a second main traffic control circuit including back contacts of said direction stick relays and of said first traffic locking relay, means controlled by said second traffic control relay while energized for controlling the signals for said second direction to display proceed indications, means controlled by said direction stick relays for signals for traffic movements in said second direction upon becoming energized consecutively in response to a train moving over said stretch of track for retaining said second traffic control relay energized over consecutively shorter portions of said second main traffic control circuit, and means controlled by a train upon passing each of said signals for controlling the corresponding signal to display a stop indication.

3. In railway traffic controlling apparatus for a stretch of railway track which is provided with a plurality of signals for governing traffic movements in a given or first direction and in the opposite or second direction over said stretch of track which comprises a plurality of blocks one for each signal for each direction of traffic movements, the combination comprising, a first traffic control relay, a second traffic control relay, a first traffic locking relay, a second traffic locking relay, a plurality of direction stick relays one for each of said signals, means controlled by a train upon passing each of said signals while the signal is controlled to display a proceed indication for energizing the corresponding direction stick relay and for then keeping the direction stick relay energized while the stretch of track is occupied between the corresponding signal and the next signal in advance which governs traffic movements in the same direction, first manually controllable means for energizing said first traffic locking relay, means including a front contact of said first traffic locking relay for energizing said first traffic control relay over a first main traffic control circuit which includes a back contact of each of said direction stick relays and of said second traffic locking relay, means controlled by said first traffic control relay while energized for controlling the signals for said first direction to display proceed indications, means controlled by said direction stick relays for signals for traffic movements in said first direction upon becoming energized in response to a train moving over said stretch of track for retaining said first traffic control relay energized, second manually controllable means for energizing said second traffic locking relay, means including a front contact of said second traffic locking relay for energizing said second traffic control relay by a second main traffic control circuit including back contacts of said direction stick relays and of said first traffic locking relay, means controlled by said second traffic control relay while energized for controlling the signals for said second direction to display proceed indications, means controlled by said direction stick relays for signals for traffic movements in said second direction upon becoming energized in response to a train moving over said stretch of track for retaining said second traffic control relay energized, and traffic controlled means for controlling each of said signals to display a stop indication while

the first block in advance of the corresponding signal is occupied by a train.

4. In railway traffic controlling apparatus for a stretch of railway track which is provided with a plurality of signals for governing traffic movements in a given or first direction and in the opposite or second direction over said stretch of track which comprises a plurality of blocks one for each signal for each direction of traffic movements, the combination comprising, a first traffic control relay, a second traffic control relay, a plurality of direction stick relays one for each of said signals, means controlled by a train upon passing each of said signals while the signal is controlled to display a proceed indication for energizing the corresponding direction stick relay and for then retaining the direction stick relay energized while the train occupies the stretch of track between the corresponding signal and the next signal in advance which governs traffic movements in the same direction as the corresponding signal, first manually controllable means for energizing said first traffic control relay over a first main traffic control circuit which includes a back contact of each of said direction stick relays, means controlled by said first traffic control relay while energized and by traffic responsive means for controlling each of the signals for said first direction to display a proceed indication if the first block in advance of the corresponding signal is unoccupied, means controlled by said direction stick relays for signals for traffic movements in said first direction upon becoming energized in response to a train moving over said stretch of track for retaining said first traffic control relay energized as long as said stretch of track is occupied, second manually controllable means for energizing said second traffic control relay over a second main traffic control circuit which includes a back contact of each of said direction stick relays, means controlled by said second traffic control relay while energized and by traffic responsive means for controlling each of the signals for said second direction to display a proceed indication if the first block in advance of the corresponding signal is unoccupied, and means controlled by said direction stick relays for signals for traffic movements in said second direction upon becoming energized in response to a train moving over said stretch of track for retaining said second traffic control relay energized as long as said stretch of track is occupied.

5. In railway traffic controlling apparatus for a stretch of railway track which is provided with a plurality of signals for governing traffic movements in a given or first direction and in the opposite or second direction over said stretch of track which comprises a plurality of blocks one for each signal for each direction of traffic movements, the combination comprising, a first traffic control relay, a second traffic control relay, a plurality of direction stick relays one for each of said signals, means controlled by a train upon passing each of said signals while the signal is controlled to display a proceed indication for energizing the corresponding direction stick relay and for then retaining the direction stick relay energized while the train occupied the stretch of track between the corresponding signal and the next signal in advance which governs traffic movements in the same direction as the corresponding signal, means responsive to a train approaching within a given distance in the rear of the first signal for said first direction for energizing said first traffic control relay over a first main traffic control circuit which includes a back contact of each of said direction stick relays, means controlled by said first traffic control relay while energized and by traffic responsive means for controlling each of said signals for said first direction to display a proceed indication if the first block in advance of the corresponding signal is unoccupied, means controlled by said direction stick relays for signals for traffic movements in said first direction upon becoming energized in response to a train moving over said stretch of track for retaining

said first traffic control relay energized as long as said stretch of track then remains occupied, means responsive to a train approaching within a given distance in the rear of the first signal for said second direction for energizing said second traffic control relay over a second main traffic control circuit which includes said back contacts of said direction stick relays, means controlled by said second traffic control relay while energized and by traffic responsive means for controlling each of said signals for said second direction to display a proceed indication if the first block in advance of the corresponding signal is unoccupied, and means controlled by said direction stick relays for signals for traffic movements in said second direction upon becoming energized in response to a train moving over said stretch of track for retaining said second traffic control relay energized as long as said stretch of track then remains occupied.

long as said stretch of track which remains occupied.

6. In railway traffic controlling apparatus for a stretch of railway track which is provided with a plurality of signals for governing traffic movements in a given or first direction and in the opposite or second direction over said stretch of track which comprises a plurality of blocks one for each signal for each direction of traffic movements, the combination comprising, a first traffic control relay, a second traffic control relay, a plurality of direction stick relays one for each of said signals, means controlled by a train upon passing each of said signals while the signal is controlled to display a proceed indication for energizing the corresponding direction stick relay and for then retaining the direction stick relay energized while the train occupies the stretch of track between the corresponding signal and the next signal in advance which governs traffic movements in the same direction as the corresponding signal, means for energizing said first traffic control relay over a first main traffic control circuit which includes a back contact of each of said direction stick relays, means controlled by said first traffic control relay while energized and by traffic responsive means for controlling each of the signals for said first direction to display a proceed indication if the first block in advance of the corresponding signal is unoccupied, means controlled by said direction stick relays for signals for traffic movements in said first direction upon becoming energized in response to a train moving over said stretch of track for retaining said first traffic control relay energized over consecutively shorter portions of said first main traffic control circuit, means for energizing said second traffic control relay over a second main traffic control circuit which includes said back contacts of said direction stick relays, means controlled by said second traffic control relay while energized and by traffic responsive means for controlling each of the signals for said second direction to display a proceed indication if the first block in advance of the corresponding signal is unoccupied, and means controlled by said direction stick relays for signals for traffic movements in said second direction upon becoming energized in response to a train moving over said stretch of track for retaining said second traffic control relay energized over consecutively shorter portions of said second main traffic control circuit.

7. In railway traffic controlling apparatus for a stretch of railway track which is provided with a plurality of signals for governing traffic movements in a given or first direction and in the opposite or second direction over said stretch of track which comprises a plurality of blocks one for each signal for each direction of traffic movements, the combination comprising, a first and a second traffic control relay both of which are normally deenergized, a plurality of signal control relays one for each of said signals all normally deenergized, a plurality of direction stick relays one for each of said signals all normally deenergized, means controlled by a train upon passing each of said signals while the corresponding signal control relay is energized for energizing the corre-

sponding direction stick relay, means controlled by the corresponding signal control relay in its deenergized condition for then retaining the corresponding direction stick relay energized while the first block in advance of the corresponding signal is occupied, means for energizing said first traffic control relay over a first main traffic control circuit which includes a back contact of each of said direction stick relays, means controlled by said first traffic control relay while energized and by traffic responsive means for the last block in said stretch of track for traffic movements in said first direction for energizing the signal control relay for the signal which governs traffic movements in said first direction over said last block if said last block is unoccupied, means controlled by each of said signal control relays when energized for effecting energization of the signal control relay for the next signal for traffic movements in the same direction in the rear of the corresponding signal if the block between the corresponding signal and the next signal in the rear is unoccupied, means for energizing said second traffic control relay over a second main traffic control circuit which includes a back contact of each of said direction stick relays, means controlled by said second traffic control relay while energized and by traffic responsive means for the last block in said stretch of track for traffic movements in said second direction for energizing the signal control relay for the signal which governs traffic movements in said second direction over said last block if said last block is unoccupied, means controlled by each of said direction stick relays for said first direction while energized for retaining said first traffic control relay energized, means controlled by each of said direction stick relays for said second direction while energized for retaining said second traffic control relay energized, and means controlled by each of said signal control relays in the energized condition for controlling the corresponding signal to display a proceed indication.

8. In railway traffic controlling apparatus for a stretch of railway track which is provided with a plurality of signals for governing traffic movements in a given or first direction and in the opposite or second direction over said stretch of track which comprises a plurality of locks one for each signal for each direction of traffic movements, the combination comprising, a plurality of direction stick relays one for each of said signals, a first traffic control relay adjacent the leaving end of said stretch for traffic movements in said first direction, a first main traffic control circuit including a back contact of each of said direction stick relays supplied with current adjacent the entrance end of said stretch for traffic movements in said first direction for energizing said first traffic control relay, a second traffic control relay adjacent the leaving end of said stretch for traffic movements in said second direction, a second main traffic control circuit including a back contact of each of said direction stick relays supplied with current adjacent the entrance end of said stretch for traffic movements in said second direction for energizing said second traffic control relay, means controlled by a train upon passing each of said signals while the signal is controlled to display a proceed indication for energizing the corresponding direction stick relay and for then retaining the corresponding direction stick relay energized while the train occupies the block for the corresponding signal, means controlled by said direction stick relays for signals for traffic movements in said first direction upon becoming energized in response to a train for retaining said first traffic control relay energized over consecutively shorter portions of said first main traffic control circuit ahead of the train, means controlled by said direction stick relays for signals for traffic movements in said second direction upon becoming energized in response to a train for retaining said second traffic control relay energized over consecutively shorter portions of said second main

traffic control circuit ahead of the train, and means controlled by each of said traffic control relays while energized and by traffic responsive means for controlling each of the signals for the corresponding direction of traffic movements to display a proceed indication if the block for the corresponding signal is unoccupied.

9. In railway traffic controlling apparatus for a stretch of railway track containing a switch and provided with a plurality of signals for governing traffic movements in a given or first direction and in the opposite or second direction over said stretch of track, the combination comprising, a first and a second traffic control relay normally connected in series with each other in a closed circuit path without a source of current, said first traffic control relay located adjacent the leaving end of said stretch for traffic movements in said first direction and said second traffic control relay located adjacent the leaving end of said stretch for traffic movements in said second direction, a first traffic control circuit including a portion of said closed circuit path supplied with energy adjacent the entering end of said stretch for traffic movements in said first direction for energizing said first traffic control relay, a second traffic control circuit including a portion of said closed circuit path supplied with energy adjacent the entering end of said stretch for traffic movements in said second direction for energizing said second traffic control relay, a signal control relay for each of said signals, means controlled by each of said signal control relays when energized for controlling the corresponding signal to display a proceed indication, means controlled by said first traffic control relay while energized and by traffic responsive means for completing the control circuit for the signal control relay for each of said signals which governs traffic movements in said first direction if a corresponding portion of said stretch of track is unoccupied, means controlled by said second traffic control relay while energized and by traffic responsive means for completing a control circuit for the signal control relay for each of said signals which governs traffic movements in said second direction if a corresponding portion of said stretch of track is unoccupied, an electric lock which when deenergized while said switch is in a normal position prevents movement of said switch to a reverse position, a first switch lock control relay for said first direction, a second switch lock control relay for said second direction, a padlock, a switch indication relay, means controlled by said padlock for normally energizing said switch indication relay while said padlock is in position for locking said switch, said switch indication relay becoming deenergized when said padlock is removed for unlocking said switch, means controlled by said switch indication relay upon becoming deenergized for disconnecting the signal control relay for the signal in each direction from the switch which governs traffic movements over said switch from the corresponding signal control circuit and connecting the corresponding switch lock control relay to each of these signal control circuits, means controlled by said switch indication relay in the deenergized condition for supplying energy to said closed circuit path for energizing said first and second traffic control relays, and means controlled by said first and second switch lock control relays both in the energized condition for energizing said electric lock.

10. In railway traffic controlling apparatus for a stretch of railway track containing a switch and provided with a plurality of signals for governing traffic movements in a given or first direction and in the opposite or second direction over said stretch of track, the combination comprising, a first and a second traffic control relay, a plurality of direction stick relays one for each of said signals, a first traffic control circuit including a back contact of each of said direction stick relays for energizing said first traffic control relay, a second traffic control circuit including a back contact of each of said direction stick relays for energizing said second traffic control relay, means controlled by a train upon passing each of said

signals while the signal is controlled to display a proceed indication for energizing the corresponding direction stick relay and for then retaining the corresponding direction stick relay energized while the train occupies the portion of said stretch between the corresponding signal and the next signal in advance, means controlled by said direction stick relays for signals for said first direction while energized for retaining said first traffic control relay energized, means controlled by said direction stick relays for signals for said second direction while energized for retaining said second traffic control relay energized, a signal control relay for each of said signals, means controlled by each of said signal control relays while energized for controlling the corresponding signal to display a proceed indication, means controlled by said first traffic control relay while energized and by traffic responsive means for completing a control circuit for the signal control relay for each of said signals which governs traffic movements in said first direction if a corresponding portion of said stretch of track is unoccupied, means controlled by said second traffic control relay while energized and by traffic responsive means for completing a control circuit for the signal control relay for each of said signals which governs traffic movements in said second direction if a corresponding portion of said stretch of track is unoccupied, an electric lock which when deenergized while said switch is in a normal position locks said switch in that position, a first switch lock control relay for said first direction, a second switch lock control relay for said second direction, a padlock, a switch indication relay, means controlled by said padlock for energizing said switch indication relay while said padlock is in position for locking said switch, said switch indication relay becoming deenergized when said padlock is removed for unlocking said switch, means controlled by said switch indication relay upon becoming deenergized for disconnecting the signal control relay for the signal in each direction from said switch which governs traffic movements over said switch from the corresponding signal control circuit and connecting the corresponding switch lock control relay to each of these signal control circuits, means controlled by said switch indication relay in the deenergized condition for energizing both of said traffic control relays, means controlled by said first and second switch lock control relays both in the energized condition for energizing said electric lock, a traffic stick relay, a pickup circuit for said traffic stick relay controlled by a back contact of said switch indication relay and by front contacts of said first and second switch lock control relays, a first and a second stick circuit for said traffic stick relay controlled by a back contact of said switch indication relay and of said second switch lock control relay respectively, a third stick circuit for said traffic stick relay controlled by a back contact of said first switch lock control relay and by a front contact of said second switch lock control relay, and means controlled by said traffic stick relay upon becoming energized for energizing both of said traffic control relays and for disconnecting the signal control relay for the signal in each direction from said switch which governs traffic movements over said switch from the corresponding signal control circuit and connecting the corresponding switch lock control relay to each of these signal control circuits.

11. In railway traffic controlling apparatus for a stretch of railway track containing a switch and provided with a plurality of signals for governing traffic movements in a given or first direction and in the opposite or second direction over said stretch of track, the combination comprising, a signal control relay for each of said signals, means controlled by each of said signal control relays while energized for controlling the corresponding signal to display a proceed indication, traffic control means for said first and second directions of traffic movements, means controllable by operation of said traffic control means for said first direction and by traffic responsive means for

completing a control circuit for the signal control relay for each of the signals for said first direction if a corresponding portion of said stretch of track is unoccupied, means controllable by operation of said traffic control means for said second direction and by traffic responsive means for completing a control circuit for the signal control relay for each of the signals for said second direction if a corresponding portion of said stretch of track is unoccupied, an electric lock which when deenergized while said switch is in a normal position locks said switch in that position, a first and a second switch lock control relay for said first and second directions respectively, a padlock, a switch indication relay, means controlled by said padlock for energizing said switch indication relay only while said padlock is in position for locking said switch, means controlled by said switch indication relay upon becoming deenergized for disconnecting the signal control relay for the signal in each direction from said switch which governs traffic movements over said switch from the corresponding signal control circuit and connecting the corresponding switch lock control relay to each of these circuits, means controlled by said switch indication relay in the deenergized condition for operating said traffic control means for both directions, and means controlled by said switch lock control relays both in the energized condition for energizing said electric lock.

12. In railway traffic controlling apparatus for a stretch of railway track containing a switch and provided with a plurality of signals for governing traffic movements in a given or first direction and in the opposite or second direction over said stretch of track, the combination comprising, a signal control relay for each of said signals, means controlled by each of said signal control relays while energized for controlling the corresponding signal to display a proceed indication, traffic control means for said first and second directions of traffic movements, means controllable by operation of said traffic control means for said first direction and by traffic responsive means for completing a control circuit for the signal control relay for each of the signals for said first direction if a corresponding portion of said stretch of track is unoccupied, means controllable by operation of said traffic control means for said second direction and by traffic responsive means for completing a control circuit for the signal control relay for each of the signals for said second direction if a corresponding portion of said stretch of track is unoccupied, an electric lock which when deenergized while said switch is in a normal position locks said switch in that position, a first and a second switch lock control relay for said first and second directions respectively, a padlock, a switch indication relay, means controlled by said padlock for energizing said switch indication relay only while said padlock is in position for locking said switch, means controlled by said switch indication relay upon becoming deenergized for disconnecting the signal control relay for the signal in each direction from said switch which governs traffic movements over said switch from the corresponding signal control circuit and connecting the corresponding switch lock control relay to each of these circuits, means controlled by said switch indication relay in the deenergized condition for operating said traffic control means for both directions, means controlled by said switch lock control relays both in the energized condition for energizing said electric lock, a traffic stick relay, a pickup circuit for said traffic stick relay controlled by a back contact of said switch indication relay and by front contacts of both said switch lock control relays, a first and a second stick circuit for said traffic stick relay controlled by a back contact of said switch indication relay and of said second switch lock control relay respectively, a third stick circuit for said traffic stick relay controlled by a back contact of said first switch lock control relay and by a front contact of said second switch lock control relay, and means controlled by said traffic stick relay upon becoming

energized for operating said traffic control means for both directions.

13. In railway traffic controlling apparatus for a stretch of railway track containing a switch and provided with a plurality of signals for governing traffic movements in a given or first direction and in the opposite or second direction over said stretch of track, the combination comprising, a first and a second traffic control relay, a plurality of direction stick relays one for each of said signals, a first traffic control circuit including a back contact of each of said direction stick relays for energizing said first traffic control relay, a second traffic control circuit including a back contact of each of said direction stick relays for energizing said second traffic control relay, means controlled by a train upon passing each of said signals while the signal is controlled to display a proceed indication for energizing the corresponding direction stick relay and for then retaining the corresponding direction stick relay energized while the train occupies the portion of said stretch between the corresponding signal and the next signal in advance, means controlled by said direction stick relays for signals for said first direction while energized for retaining said first traffic control relay energized, means controlled by said direction stick relays for signals for said second direction while energized for retaining said second traffic control relay energized, a signal control relay for each of said signals, means controlled by each of said signal control relays while energized for controlling the corresponding signal to display a proceed indication, means controlled by said first traffic control relay while energized and by traffic responsive means for completing a control circuit for the signal control relay for each of said signals which governs traffic movements in said first direction if a corresponding portion of said stretch of track is unoccupied, means controlled by said second traffic control relay while energized and by traffic responsive means for completing a control circuit for the signal control relay for each of said signals which governs traffic movements in said second direction if a corresponding portion of said stretch of track is unoccupied, an electric lock which when deenergized while said switch is in a normal position locks said switch in that position, a first switch lock control relay for said first direction, a second

switch lock control relay for said second direction, a padlock, a switch indication relay, means controlled by said padlock for energizing said switch indication relay while said padlock is in position for locking said switch, said switch indication relay becoming deenergized when said padlock is removed for unlocking said switch, means controlled by said switch indication relay upon becoming deenergized for disconnecting the signal control relay for the signal in each direction from said switch which governs traffic movements over said switch from the corresponding signal control circuit and connecting the corresponding switch lock control relay to each of these signal control circuits, means controlled by said switch indication relay in the deenergized condition for energizing both of said traffic control relays, means controlled by said first and second switch lock control relays both in the energized condition for energizing said electric lock, a first and a second auxiliary direction control relay for the signal which governs traffic movements in said first and second directions respectively over said switch, an energizing circuit for said first auxiliary direction control relay including a back contact of said first switch lock control relay in multiple with a front contact of said switch indication relay, a front contact of said first auxiliary direction control relay included in the energizing means for the direction stick relay for the corresponding signal, an energizing circuit for said second auxiliary direction control relay including a back contact of said second switch lock control relay in multiple with a front contact of said switch indication relay, a front contact of said second auxiliary direction control relay included in the energizing means for the direction stick relay for the corresponding signal, and traffic responsive means for keeping each of said auxiliary direction control relays energized while said stretch of track is occupied between the corresponding signal and said switch.
